CLAIM

The ornamental design for amplifier case, as shown and described.

DESCRIPTION

FIG. 1 is a top, front, and right side isometric view of an amplifier case showing my design.

FIG. 2 is a top view thereof.

FIG. 3 is a bottom view thereof.

FIG. 4 is a front elevation view thereof.

FIG. 5 is a rear elevation view thereof; and,

FIG. 6 is a right side elevation view thereof, the left side elevation view being identical thereto.
